[57] ABSTRACT

A device for cutting a cord at any ocean depth in order to release buoys, floats, corers, mines etc. The device includes a knife blade which is held in place by a release mechanism in a loaded position which upon release forces the knife blade through the cord to release a pay load.

PROGRAMMED CORD CUTTER

BACKGROUND OF THE INVENTION

This disclosure relates to release mechanisms and more particularly to automatic releasing mechanisms for releasing objects held by a cord, line or similar element which may be severed by a cutter.

Heretofore, various complicated mechanical and electrically triggered mechanisms have been used for releasing different types of devices. Such release devices include plungers, trips, electric motors, etc. Some of these fail because of electrical and/or mechanical problems.

SUMMARY OF THE INVENTION

This invention makes use of a time controlled connector or linkage which secures a movable cutter blade in a loaded position within a housing. Upon release by the time controlled connector, the knife blade moves within the housing to sever a cord, rope, line or any suitable severable element which may be used to hold a desired object in place. The knife blade is movable within the housing which is secured to the line which supports the pay load; therefore, there is no loadstrain on the housing which holds the knife blade in place.

STATEMENT OF THE OBJECTS

It is therefore an object of the present invention to provide a simple, inexpensive, reusable device for releasing an object under time controlled conditions.

Another object is to provide a release mechanism which is capable of handling large loads compared with the size of the device.

Still another object is to provide a release mechanism which is separate from the means for holding an object to the device.

Yet another object is to store and release an energy driven cutter for cutting a line to release a desired object when desired.

BRIEF DESCRIPTION OF THE DRAWING

The drawing is a partial sectional view illustrating the relative parts of the device in perspective.

DETAILED DESCRIPTION OF THE DEVICE

Now referring to the drawing, there is shown by illustration a cutter blade release mechanism made in accordance with the teaching of this invention. As shown, the device includes a cylindrical, elongated, open ended, housing 10 which is provided with external threads 11 on one end thereof. Near the opposite end of the housing, is provided an aperture 12 perpendicular to the axis through which a dowel pin 13 is inserted to extend from opposite sides of the housing in equal amounts. Upwardly from dowel pin 13 there is provided an aperture 14 in a plane at 90° relative to the dowel pin 13. The aperture 14 is of a diameter to receive therethrough a cord, line, or rope of a sufficient size to carry a desirable payload and to which a release mechanism is secured for release of the payload. Opposite linear slots 15 are made within the housing and extending along the central section in the same plane as the dowel pin 13. A solid cylindrical, knife holder slide 16 is secured within the housing for axial movement therein by use of a dowel pin 17 which

passes through the slots 15 in the housing and an aperture 18 in the knife holder slide 16. The end of the knife holder facing the dowel pin 13 has a V-shaped thin knife blade 19 secured thereto such that the blade is in the same plane as the dowel pins 13 and 17, and perpendicular to the aperture 14 such that movement of the slide and knife blade will sever a line that passes through the aperture 14. The energy for movement of the knife blade in the housing may be provided by strong elastic bands 21 or other elastic material or springs secured to the dowel pins 13 and 17 which applies a force on the slide as the slide is moved away from the aperture 14. The end of the slide opposite from the knife blade is provided with an axially aligned aperture 22 that extends from the end surface to an aperture 23 perpendicular thereto. The housing 10 is provided with an aperture 24 upward from slots 15 in the same plane as the dowel pins and which aligns with the aperture 23 in the slide when the slide is in a loaded position. The housing is provided with an aperture 25 that only extends through one wall, a short distance from aperture 24. The slide 16 is provided with a threaded aperture 26 that extends to the axially aligned aperture 22 which receives therein a set screw 27 through aperture 25. The housing in the area above the slide is provided with additional apertures 28 through which a fluid may pass into the area bounded by the housing.

A cap 31 is screw threaded onto the threaded end of the housing and is itself provided with an axially aligned threaded aperture 32. An adapter 34 having an axially aligned hole 33 therethrough is provided with a short threaded end that threads into the axial aperture in the cap and a longer threaded end 35 that extends outwardly from the body of the adapter. The adapter may be made of a material which may serve as an electrical insulator.

The slide is secured in place by a control release mechanism 40. The release mechanism includes a rod or wire 41 that extends into the axially aligned aperture 22 in the slide and which is secured thereto by the set screw 27. A rod or wire 42 extending from the opposite end of the release mechanism is passed through the axially aligned hole 33 in the adaptor and bent around the outer threaded end of the adapter. A high voltage terminal 43 is slid over the outer threaded end 35 of the adapter and secured against the wire 42 by a terminal cap 44 which is threaded onto the adapter. If desired, a washer 45 may be placed between the wire and the body of the adapter.

The release mechanism may be made of any desired controlled element. One such controlled element is a low watt resistor which disintegrates upon a surge of high voltage electrical current being sent through the low watt resistor. The electrical surge may be controlled remotely with a suitable circuitry connected to the low watt resistor. In order to complete the circuit a ground connection must be made with the housing or the wire connected with the low watt resistor and extending from the housing.

Another type of release is a corrosive link which will corrode due to the surrounding environment such as sea water.

The cutter-release device may be light weight and small for instance — 7 1/2 inches long with an outside

diameter of $\frac{5}{8}$ inch with $\frac{1}{4}$ inch dowel pins of $1\frac{1}{2}$ inches in length. Since the release mechanism holds the knife blade slide in a loaded position against the energy of the rubber bands, the release mechanism must be of sufficient strength to secure the knife slide in place. The housing, slide, and dowel pins may be made of metal or any other desired material that will not be effected by the environment in which the device is to be used.

In assembly, the parts are all made up, dowel pin 13 is inserted into place then the knife blade slide 16 is inserted through the cap end and dowel pin 17 is inserted through the slots 15 and through aperture 18 in the slide. Without the rubber bands in place, the slide is moved to its furthest position from dowel pin 13 such that the aperture 23 in the slide aligns with the aperture 24 in the housing. The release mechanism 40 is inserted through the cap end and the inner wire 41 is inserted into the axially aligned aperture 22 in the upper end of the slide. The wire is inserted into the aperture until the end can be seen through the apertures 23 and 24. The set screw is then threaded into place against the wire thereby securing the wire in the aperture of the slide. The adapter 34 is threaded into the end cap 31 and the end cap is then threaded onto the housing with the wire 42 extending through the aperture 33 in the adapter. The end of wire 42 is then wrapped around the outer end of the adapter and any excess wire is cut off. The electrical high voltage terminal 43 is then slid over the end 35 of the adapter and the terminal cap 44 is threaded onto the outer end of the adapter thereby holding or securing the wire in place. The cutter-release is now ready for use by securing the device to a line to be severed and the rubber bands are placed on the dowels to supply energy to the slide and knife blade.

The device may be used to release any size load that can be held by a line which passes through the cord aperture and which may be severed by the knife blade. Of course, if considerable weight is being held by the line, the weight will aide in severing the line due to its weight or pull on the line.

In use, for releasing a load held by a line, the line is 45 passed through the cord aperture in the housing of the cutter-release device. With the knife blade slide secured in place by a release mechanism, an energy load is applied to the knife blade slide by placing rubber bands around the dowel pins or by use of suitable springs. The load may now be placed wherever desired. When using a low watt resistor release mechanism a high voltage current is electrically connected with the low watt resistor and when it is desired to release the load, the electrical circuit is closed and 55 the low watt resistor disintegrates thereby releasing wire 41. This permits movement of the knife blade slide toward the line thereby severing the line that passes through the cord aperture in the housing. Once the line has been severed, the load is released.

The load may be released by use of a corrosive link of the type known as "Pop-Ups" manufactured by Oceane-Tica, Inc., Miami, Fla. and described in U.S. Pat. No. 3,426,472. Time delays may be varied from a few hours to several days by selecting different size corrosive links. The delay is calculated by use of known charts. When using the corrosive link, the load to be

released is placed in salt water or other solution which attacks the material. The salt water enters the housing through the apertures 28 in the housing in the vicinity of the corrosive link thereby reacting with the material to release the knife blade slide.

For release of payloads in different surroundings, different chemical materials may be used. The materials used should be able to hold the knife blade slide in place and to be attacked by the surroundings in which the payload is to be released. Therefore, the release mechanism is chosen to be compatible with the surrounding in which the payload is to be released. Electrical releases may be more advantageous in some instances where chemical releases may be more advantages in other areas.

In some cases the knife blade may be held in place by a corrosive link and the chemical material that attacks the corrosive link may be packed around the corrosive link with a chemical reaction releasing the knife blade. Timing may be carried out experimentally. Of course, the chemical material would not be added to the housing until the payload was ready to be launched.

The cutter-release mechanism has been described as 25 using rubber bands for movement of the knife blade slide. It is obvious that other energy supplying means may be used such as springs connected to the dowels or the dowels may be removed and an internal compression spring placed between the end of the knife blade slide and the end cap of the housing. The device would be loaded in the same manner as described above.

The release mechanism may be used at any ocean depth to release oceanographic equipment or at any 35 height in the atmosphere to release upper air research devices. Further use may apply to mine laying operations.

Obviously many modifications and variations of the present invention are possible in the light of the above 40 teachings. It is therefore to be understood that within the scope of the appended claims the invention may be practiced otherwise than as specifically described.

What is claimed and desired to be secured by Letters Patent of the United States is:

1. A cutter-release device which comprises: an open ended cylindrical tubular housing, an aperture through said housing near one end thereof normal to the axis through which a line may pass, a knife blade holder slide means in said housing for axial movement therein, a knife blade held by said slide means in a plane perpendicular to said aperture through said housing through which said line may pass, a disintegratable controlled release mechanism within said housing in axial alignment with said knife blade holder slide means for securing said knife blade holder slide in a loaded position against a force load applied to said knife blade holder slide means, and means for applying a drive force to said slide means whereby said slide means is forced toward said aperture through which said line passes upon disintegration of said release mechanism.

2. A cutter-release device as claimed in claim 1; wherein,

said release mechanism is forced of a corrosive material which has a corrosive reaction when the device is placed in a desired environment thereby releasing said slide means upon disintegration of said disintegratable controlled release mechanism.

3. A cutter-release device as claimed in claim 1; wherein,

said release mechanism is a low watt resistor which disintegrates upon passage of a high current surge through said resistor thereby releasing said slide.

4. A cutter-release device as claimed in claim 1; wherein,

said force applying means is an elastic material.
